UNITED STATES PATENT OFFICE.

HEINRICH SEIBERT, OF BERLIN, GERMANY.

ELECTRIC HEATING FURNACE.

Application filed August 16, 1923. Serial No. 657,775.

To all whom it may concern:

Be it known that I, HEINRICH SEIBERT, a citizen of the German Republic, residing at Berlin, Germany, have invented certain new and useful Improvements in Electric Heating Furnaces, for which I have filed applications for patent in Germany, Feb. 16, 1922, and March 8, 1923, and of which the following is a specification.

10 This invention relates to electric heating furnaces with granular resistance material. In these electric furnaces, especially in muffle furnaces, a muffle exists around which the resistance material is accommodated in hollow spaces. The use of such muffles especially in larger sized furnaces requires corresponding thickness of the wall even if the muffles are composed of several parts. The material from which the muffles 20 are made, namely, fire brick, is a poor conductor of heat, and consequently is a serious obstacle in the transmission of heat produced in the resistance material to the heat chamber. Especially at high temperatures 25 over 1000° C. it therefore happens sometimes that the temperature in the heating spaces is higher by several hundred degrees than the temperature in the real heating chamber, whereby excessive heat results 30 in the heating spaces and consequently damaging of the material of the muffle and loss of current. The poor results of such furnaces are mainly caused by these inconveniences.

35 According to the invention these inconveniences are avoided by forming the walls of the heating chamber entirely or partly of projecting heating pipes containing granular resistance material, in order to obtain 40 the largest possible heating surface and to protect at the same time the refractory parts. These heating pipes are preferably built in so that they are easily exchangeable and eventually non-supported. The heating 45 pipes may be of convenient cross-section. If they are of rectangular cross section and if adjacent faces of two heating pipes are inclined the one to the other the heat is especially well transmitted to the inner 50 chamber.

In order to prevent a mutual over-heating of the heating pipes they are arranged at a determined distance apart. The air gaps between the heating pipes may extend into 55 the brick work of the furnace. They pre-

vent also the production of short-circuits between the pipes.

The heating pipes extend preferably through openings in the ceiling of the furnace so that they may be exchanged simply by being removed, and a damaged heating pipe may be exchanged for a new one or fitted with new resistance material.

This construction allows the pipes to be refilled at any time with new resistance material without removing the pipes.

This improved furnace has, in comparison with the furnaces of known type, an especially good heating effect owing to the large heating surface, and consequently a greater 70 efficiency. The heating can be rapidly started and the material of which the furnace is built is preserved and higher temperatures can be produced with material of equal refractoriness. 75

The invention will be best understood from a consideration of the following detailed description taken in connection with the accompanying drawings forming a part of this specification, with the understanding 80 that while on the drawing several embodiments of the invention are disclosed, the invention is not confined to any strict conformity with the showing of the drawings, but may be embodied in any manner which 85 does not make a material departure from the salient features of the invention.

In the drawing:

Fig. 1 is a vertical cross sectional view of the furnace on line A—B of Fig. 3. 90

Fig. 2 is a vertical longitudinal sectional view of the furnace on line C—D of Fig. 3.

Fig. 3 is a horizontal cross section on line E—F of Fig. 1.

Fig. 4 shows in plan view the second form 95 of construction, the top plate being removed.

Fig. 5 shows in elevation a single heating pipe.

The walls of the furnace *a* consist of refractory material. On the inner surfaces of 100 the walls heating pipes *b*, *b'*, *b''* are arranged. The heating pipes *b* are of trapezoidal cross section so that the adjacent faces of two heating pipes are inclined with regard to one another, the heat being consequently 105 well transmitted in inward direction. Between two adjacent heating pipes *b* air gaps are formed which extend into the wall *a* of the furnace and prevent a direct contact and a direct transmission of heat from one 110

heating pipe to the other and consequently also mutual excessive heating of the heating pipes. These air gaps prevent farther the production of short-circuit between the heating pipes.

5 The heating pipes b are of rectangular cross section and the heating pipes b^2 are of circular cross section. In one furnace only heating pipes of the same cross section are 10 preferably used; but heating pipes of different cross sections might be used, as shown, in the same furnace to ensure radiations of different strengths in the different parts of the furnace.

15 In order to improve the radiation of the heat from the walls, this heat having been radiated from the heating pipes b^2 on the walls, the walls have rib-shaped projections c .

20 Each heating pipe consists of an outer pipe of refractory material being filled with granular resistance material. An electrode d is inserted through the bottom of the pipe. The upper end of the heating pipe is closed 25 by a cap f through which an electrode d is inserted. This cap may be omitted.

The neck of the pipe is mounted in the bottom of the furnace a the upper end of the pipe extending through the top plate g 30 of the furnace. If one of the pipes should be damaged it may be removed from the furnace in upward direction after the electric connection has been loosened, a new pipe being inserted instead.

35 The bottom is heated by means of resistance material mounted in a cavity of the bottom. Current is supplied to this resistance material by electrodes d' . The resistance material in the bottom is covered by a 40 refractory plate i which prevents the access of air to the resistance material. The opening k for the door is closed by a plate l . In

the rear wall of the furnace a peep hole, not shown, may be arranged which is closed in a convenient manner.

45 The top plate g is placed upon the upper edge of the furnace.

In the form of construction shown in Figs. 1-3 the furnace is of rectangular cross section. It could be of circular cross section as 50 shown in Fig. 4. The construction of this furnace of circular cross section is otherwise similar to that of the form of construction shown in Figs. 1-3.

55 I claim:—

1. In an electric furnace, resistance elements comprising casings of refractory material and granular resistance material therein, said casings having their lateral faces inwardly inclined whereby wedged shaped air 60 gaps are formed between said resistance elements.

2. In an electric furnace, resistance elements comprising casings of refractory material and granular resistance material therein, said casings being disposed along the furnace walls, and air gaps between said casings and extending into the furnace walls.

65 3. In an electric furnace, resistance elements comprising casings of refractory material and granular resistance material therein, said casings being disposed along the furnace walls and having inwardly inclined faces whereby wedged shaped air gaps are 70 formed between said resistance elements, 75 said air gaps being extended into the furnace walls.

In testimony whereof I affix my signature in presence of two witnesses.

HEINRICH SEIBERT.
